[57] CLAIM

The ornamental design for electrophotographic apparatus or the like, substantially as shown and described.

DESCRIPTION

FIG. 1 is a top, right side and front perspective view of an electrophotographic apparatus or the like showing our new design.

FIG. 2 is a top, left side and rear perspective view thereof.

The bottom view of the electrophotographic apparatus is planar and substantially unornamented.

FIG. 1

FIG. 2
